US00D591156S

(12) **United States Design Patent**
George et al.

(10) **Patent No.:** **US D591,156 S**
(45) **Date of Patent:** **** Apr. 28, 2009**

(54) **BOTTLE**

(75) Inventors: **Patrick T. George**, Plano, TX (US);
Nicholas J. Caporin, Little Elm, TX
(US); **Christopher Thompson**
Caldwell, Monroe, MI (US)

(73) Assignee: **Snapple Beverage Corporation**, Plano,
TX (US)

(**) Term: **14 Years**

(21) Appl. No.: **29/317,517**

(22) Filed: **Apr. 30, 2008**

(51) **LOC (9) Cl.** **09-01**

(52) **U.S. Cl.** **D9/516; D9/552; D9/565**

(58) **Field of Classification Search** **D9/516,**
D9/522, 529, 530, 537, 539, 540, 549, 551,
D9/552, 554, 555, 556, 557, 558, 564, 565,
D9/567, 569, 570, 574, 575; 215/381-385

See application file for complete search history.

(57) **CLAIM**

The ornamental design for a bottle, as shown and described.

DESCRIPTION

FIG. 1 is a perspective view showing our new design;

FIG. 2 is a front elevational view thereof;

FIG. 3 is a right elevational view thereof;

FIG. 4 is a rear elevational view thereof;

FIG. 5 is a left elevational view thereof;

FIG. 6 is a top plan view thereof; and,

FIG. 7 is a bottom plan view thereof.

The broken lines showing environment are for illustrative purposes only and form no part of the claimed design.

1 Claim, 4 Drawing Sheets
